UNITED STATES PATENT OFFICE.

RAY P. JACKSON, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

IRON-PORCELAIN INSULATING-BUSHING.

1,199,467.

Specification of Letters Patent. Patented Sept. 26, 1916.

Application filed June 9, 1914. Serial No. 843,948.

To all whom it may concern:

Be it known that I, RAY P. JACKSON, a citizen of the United States, and a resident of Edgewood Park, in the county of Alle-

gheny and State of Pennsylvania, have invented a new and useful Improvement in Iron - Porcelain Insulating - Bushings, of which the following is a specification.

My invention relates to electrical insulating structures, and it refers to bushings which are adapted to insulate high-potential conductors from walls of casings or tanks in which transformers or other electric apparatus associated with the high-potential conductors may be disposed. However, it will be understood that my invention may be utilized also in high-voltage outlet structures for power stations, transformer sub-stations, etc., where it is necessary to bring high-potential transmission conductors through the walls or roofs of the station building.

The usual porcelain insulating bushings which have corrugated surfaces or a plurality of superposed petticoats are liable to be broken when located in places where they are exposed to severe mechanical shocks and strains. To insure them against breakage, porcelain insulators are of a cumbersome construction in order to provide sufficient strength to resist the strains imposed upon them. As a result, the weight of such insulators makes them difficult to handle, and increases their cost of construction. By means of my invention, I provide an insulating bushing which is particularly adapted for severe service conditions, because the exposed petticoats are made of cast iron or some other material which is capable of withstanding very severe mechanical shocks and strains. Furthermore, my insulating bushing may be utilized to insulate very high-voltage conductors and, at the same time, be smaller in size and simpler in construction than insulating bushings of the usual porcelain type heretofore constructed for similar service conditions.

For a better understanding of the nature and the scope of my invention, reference may be had to the following description and the accompanying drawing in which—

Figure 1 is a cross sectional view of an insulating bushing constructed in accordance with my invention, and Fig. 2 is a cross

sectional view showing a conductor threaded 55 through a condenser-type bushing which, in turn, is embraced by a bushing embodying a form of my invention.

Referring to Fig. 1, a high-potential conductor 2 is embraced by a bushing 3 which 60 comprises a continuous inner tube 4 surrounded by a series of superposed and telescoped porcelain tubular members or cylinders 5. The internal and external diameters of one half of each cylinder 5 are less 65 than the diameters of the other half which permits the cylinders to be nested into one another, as shown in the drawing. The uppermost cylinder 6 is provided, at its upper portion, with a metallic cap 7 having a central opening 7a through which the rod 2 projects. The electrical connections between the rod 2 and the transmission conductor or other apparatus (not shown) is effected by means of any suitable means engaging the 75 cap 7.

The portions of the bushing 3 which are exposed to mechanical shocks constitute a series of superposed metallic conducting members or petticoats 8 made of cast iron or 80 other suitable material. The edge of the opening in each petticoat merges into a bead 9 which engages the insulating cylinders 5 at their mid points or elbows 10. With the exception of the uppermost petticoat 8, each 85 petticoat is interposed between two adjacent and superposed cylinders 5, and is maintained rigidly in position by means of Portland cement 11 which adheres to the metallic petticoat 8 and the adjacent surfaces of the 90 cylinders 5. Bridging the spaces between adjacent petticoats 8, are bodies 12 of insulating material which is capable of being molded and has high dielectric strength, such as an insulating gum of a variety well 95 known in the art. For maximum efficiency, the material 12 between each adjacent pair of the metal petticoats 8 is so molded as to provide a leakage surface therebetween which conforms to the direction of the electrostatic flow lines between the conducting members 1 and 6. To preclude the deterioration of the molded material 12, and to provide leakage paths of permanently high resistance, annular porcelain members 13 of 100 inverted substantially frusto-conical shapes, engage the exposed surfaces of the molded material. It will be understood that it is

not essential to have the exposed insulating surfaces conform to the direction of the electrostatic flow lines representing the electric field between the conducting members, but, 5 in high-voltage installations, it is desirable to design the insulating bushings in accordance with this principle in order to obtain the maximum insulating strength of the bushing.

10 In constructing the bushing, the adjacent porcelain cylinders 5 are built up, and insulating gum 14 is interposed between adjacent surfaces of the upper half of the lower cylinder, and the lower half of the upper cylinder. The space between the rod 2 and the inner tube 4 may be likewise filled with a suitable insulating gum.

It is apparent that it will be necessary to supply each bushing with a plurality of conducting petticoats 8, insulated from one another by means of the nested porcelain insulators 5, the total number of conducting members for each bushing depending upon the service conditions to which the 25 bushing is to be subjected. The conducting members 8 are adequately insulated from one another, and the porcelain members 13 are interposed therebetween to provide permanent leakage paths of high resistance. The petticoats 8 extend laterally 30 beyond the members 13, thereby shielding them from rain and mechanical blows which would either decrease or deteriorate their insulating qualities, or lessen the resistance 35 of the leakage paths. Again, the porcelain cylinders 5 are subjected only to compressive stresses which porcelain is particularly adapted to resist.

While I have shown porcelain members 40 13 engaging the exposed surfaces of the insulating material 12, it is not necessary that these porcelain members be supplied. However, it is preferable to protect the exposed surfaces of the molded material 12, inasmuch as it may become honeycombed and 45 filled with particles of dust and other matters which will decrease its insulating properties. As a result, the resistance of the leakage path between the adjacent petticoats 8 will be decreased unless the porcelain members 13 are utilized to protect the exposed surfaces of the insulating material 12. Again, porcelain material may be readily molded into various shapes before being 50 glazed. This property particularly adapts porcelain for use where the exposed insulating surface should conform to electrostatic flow lines, as mentioned above.

Referring to Fig. 2, an inner bushing 15 60 of the condenser type of construction, which comprises a plurality of layers of alternately insulating and conducting materials, embraces a metallic tube 16 which constitutes the high-potential conductor. The 65 exposed portion of the bushing 15 is inclosed

by a bushing built in accordance with my invention. The frusto-conical end of the condenser bushing is hermetically sealed in position within the bushing 3 by means of an insulating gum or compound 17. Inasmuch as the electrostatic stresses are equalized and the electrostatic lines are uniformly distributed by reason of the bushing 15, the porcelain members 13 which constitute the leakage paths between adjacent petticoats 8, 70 75 are of similar form and shape throughout the length of the built-up structure. In other respects, the exterior bushing shown in Fig. 2 corresponds to the bushing of Fig. 1, which is fully described above. 80

My invention is, of course, not restricted to any particular application, and I desire that the scope shall be limited only by the appended claims.

I claim as my invention:

85 1. An insulating structure comprising a series of superposed and telescoped insulating tubular members to provide double walls, a plurality of laterally extending annular conducting members, the inner rim of each being interposed between adjacent pairs of said insulating members, and additional insulating bodies bridging the spaces between the said adjacent conducting members.

90 2. An insulating structure comprising a series of superposed insulating tubular members, the lower portion of each overlapping with the upper portion of the next succeeding one to provide double walls, a 100 plurality of annular conducting members having their inner rims interposed between adjacent pairs of said insulating members, and additional insulating bodies bridging the spaces between the adjacent conducting members.

105 3. An insulating bushing comprising a 110 series of superposed insulating tubular members having elbows formed intermediate their ends, a plurality of annular conducting members engaging the tubular members at said elbows, and insulating 115 bodies bridging the spaces between adjacent conducting members, said conducting members extending laterally beyond the insulating material.

120 4. An insulating bushing comprising a 125 series of superposed and telescoped insulating tubular members having elbows formed intermediate their ends, a plurality of laterally and downwardly extending annular conducting members engaging said elbows of the insulating members, and insulating material so shaped as to conform to the electrostatic flow lines bridging the spaces between adjacent conducting members.

130 5. An insulating bushing comprising a

series of superposed insulating cylinders having elbows formed intermediate their ends, a plurality of annular conducting members engaging the cylinders at said elbows, and additional porcelain members bridging the spaces between adjacent conducting members in order to provide leakage paths therebetween of permanently high resistance, the said conducting members ex-

tending laterally beyond the porcelain 10 members.

In testimony whereof, I have hereunto subscribed my name this 22nd day of May, 1914.

RAY P. JACKSON.
